DESIGN FOR A FLUORESCENT LIGHTING FIXTURE

John F. Livers, Decatur, Ill., assignor to Faries
Manufacturing Company, Decatur, Ill., a cor-
poration of Illinois

Application July 24, 1940, Serial No. 93,890

Term of patent 7 years

To all whom it may concern:

Be it known that I, John F. Livers, a citizen
of the United States, residing at Decatur, in the
county of Macon and State of Illinois, have
invented a new, original, and ornamental Design
for a Fluorescent Lighting Fixture, of which the
following is a specification, reference being had
to the accompanying drawing, forming part
thereof, in which:

Figure 1 is an end elevational view of the
fluorescent lighting fixture showing my new de-
sign.

Figure 2 is a bottom plan view thereof.

I claim:

The ornamental design for a fluorescent light-
ing fixture, as shown.

JOHN F. LIVERS.
